(57) **CLAIM**

The ornamental design for a corner post for cable railing system, as shown and described.

DESCRIPTION

FIG. 1 is a perspective view of a corner post for cable railing system showing my new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a top view thereof; and,

FIG. 7 is a bottom view thereof.

Portions shown in broken lines are for purposes of illustrating the environment in which the corner post for cable railing system embodied in my design is used, and form no part of my claimed design.
